(57) **CLAIM**

The ornamental design for an electric hydraulic jack, as shown and described.

DESCRIPTION

FIG. 1 is a front and top perspective view of an electric hydraulic jack, showing my new design;

FIG. 2 is a rear and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of a portion indicated in FIG. 1.

The broken lines in the figures illustrate portions of the electric hydraulic jack that form no part of the claimed design.

The dot-dash lines shown in FIG. 9 are to show an enlarged area and form no part of the claimed design.
